UNITED STATES PATENT OFFICE.

FRANCIS F. PATTON, OF CHICAGO, ILLINOIS, ASSIGNOR TO DELTA TAU DELTA FRATERNITY, A CORPORATION OF NEW YORK.

DESIGN FOR A BADGE.

Application filed September 8, 1924. Serial No. 10,696. Term of patent 14 years.

To all whom it may concern:

Be it known that I, FRANCIS F. PATTON, a citizen of the United States, residing at Chicago, county of Cook, and State of Illinois, have invented a new, original, and ornamental Design for a Badge, of which the following is a specification, reference being had to the accompanying drawing, forming a part thereof.

I claim:

The ornamental design for a badge as shown.

FRANCIS F. PATTON.
